UNITED STATES PATENT OFFICE

2,383,675

WATER HEATER CONTROL SYSTEM

Clark M. Osterheld, Stoughton, Wis., assignor to
McGraw Electric Company, Elgin, Ill., a corporation of Delaware

Application March 20, 1944, Serial No. 527,302

5 Claims. (Cl. 219—39)

My invention relates to electric heating and particularly to control systems for the electric heaters of hot water tanks.

Among the objects of my invention are the following: to provide a water heater control system for the heater of a domestic hot water tank that shall be effective to cause energization of the heater immediately upon nightfall in case a relatively large amount of hot water has been withdrawn from the tank during daylight hours and that shall prevent energization of the heater except after a predetermined period of time delay in case only a relatively small quantity of hot water has been so withdrawn from the tank; to provide a heater control system that shall be effective to cause energization of the electric heater of a domestic hot water tank in case of withdrawal of hot water from the tank during daylight hours.

Other objects of my invention will either be apparent from a description of one control system embodying my invention or will be pointed out in the course of such description and set forth particularly in the appended claims.

In the drawing,

Figure 1 is a vertical section through a domestic hot water tank, having associated therewith a control system embodying my invention, and,

Fig. 2 is a diagram of connections of my improved control system.

Referring first to Fig. 1 of the drawing, I have there shown a domestic hot water tank 11 having a lower cold water inlet pipe 13 and an upper hot water outlet pipe 15. The tank 11 may be surrounded by a mass 17 of heat-insulating material, which material may be held in proper operative position around the tank 11 by an outer casing 19. I provide preferably, but not necessarily, a single electric heater 21 which, if only a single electric heater is provided, is preferably positioned around the tank 11 adjacent to the lower end thereof and may be positioned in a tunnel member 23. The electric heater 21 is preferably, but not necessarily, of a clamp-on type, adapted to be secured in good heat-conducting relation to the outside surface of the tank 11 adjacent the bottom end portion thereof.

I provide a first thermally-actuable heater control switch 25, which is shown schematically, or generally only, as comprising a bimetal bar 27, having one end portion thereof connected to a contact member 29, which is positioned in heat-receiving relation relatively to the tank 11 just above the heater 21. Switch 25 includes also a fixed contact member 31, which is adapted to be engaged by and disengaged from the bimetal bar 27

27 to close and open the heater control circuit of heater 21.

I provide also a thermal retarder switch 33, which is indicated in Fig. 1 of the drawing generally only, and the details of which are to be found in my copending application, S. N. 511,387, filed November 22, 1943, and assigned to the same assignee as is the present application. Briefly, such thermal retarder includes a first expansion rod 35, which is relatively highly expansible and which is supported in heat-receiving relation relatively to the water in the tank 11 as by a heat-conducting support 37. The thermal retarder 33 includes also a second expansion rod 39, which is of relatively low thermal expansivity, as compared to rod 35. For illustrative purposes only, the rod 35 may be made of aluminum, while rod 39 may be made of a nickel steel having a thermal expansivity on the order of one-half of that of the high expansion rod 35. The two rods 35 and 39 are adapted to support a switch arm 41, which is adapted to engage with and be disengaged from a pair of fixed contact members 43 and 45. While no electric insulation has been shown, it is to be understood that such is provided in the design and construction of the thermal retarder 33. The low expansion rod 39 is supported on a block 47 of heat-insulating material on support 37 and extends substantially parallel axially, relatively to the high expansion rod 35.

When the temperatures of rods 35 and 39 are on the order of the ordinary room temperature, say 70° F., the lengths of the two rods 35 and 39 35 will be substantially alike, with the result that the switch arm 41 will be in engagement with contact members 43 and 45. When the thermal retarder 33 is subject to hot water in the tank, the length of the high expansion rod 35 will be greater 40 than that of rod 39, with the result that switch arm 41 will be disengaged from contact members 43 and 45.

A low-wattage heating coil 49 is operatively associated with the low expansion rod 39, and after 45 coil 49 has been energized for a predetermined length of time, on the order of five or six hours, the temperature of rod 39 will have been raised to a value on the order of 300°, with the result that the axial length of rod 39 is again substantially 50 equal to that of rod 35 when rod 35 has been heated to a temperature on the order of 150° F., which is that of the ordinary hot water in a domestic tank. When the lengths of rods 35 and 39, when heated to 150° F. and 300° F. respectively, 55 are substantially equal, switch arm 41 will again

be in engagement with contact members 43 and 45.

While I have illustrated and described a particular form of thermal retarder, I do not desire to be limited thereto, since other thermal retarders effective for the same general purpose, as has been hereinbefore set forth, may be substituted therefor without departing from the spirit and scope of my invention.

A light sensitive cell 51, here shown generally only as a selenium cell, is provided. This cell 51 is adapted to permit the flow of electric current therethrough when subjected to daylight, and it is to be understood that cell 51 is to be positioned in such manner as to be subject to daylight during daylight hours.

I provide a pair of supply circuit conductors 53 and 55, and one terminal of cell 51 is adapted to be connected by a conductor 57 with the first supply circuit conductor 53.

I provide an electromagnetic heater control switch designated in its entirety by numeral 59, this switch including, in addition to two fixed contacts 61 and 63, a contact bridging member 65 connected with a magnetizable armature core 67, having an energizing coil 69 wound therearound, all in a manner well known in the art. Switch 59 is adapted to be in closed position when no current is flowing through coil 69 and to be in open position when a current is flowing therethrough. The other terminal of cell 51 is adapted to be connected to one terminal of coil 69, the other terminal of which is connected by a conductor 71 with the second supply circuit conductor 55. When cell 51 is in proper operative condition, the contact bridging member 65 will therefore be in engagement with contacts 61 and 63 during the hours of night and will be out of engagement therewith during daylight hours.

I provide a second electromagnetic switch 73, comprising a pair of fixed contacts 75 and 77, adapted to be engaged by and disengaged from a contact bridging member 79. Contact bridging member 79 is mechanically connected with a magnetizable core 81, which core is adapted to be energized by a coil 83. One terminal of coil 83 is connected by a conductor 85 to a conductor 87 which connects the second supply circuit conductor 55 to terminal 29 of the first lower thermally-actuable heater control switch 25.

I provide further a thermal timer 89, comprising a bimetal bar 91, having one end fixedly secured to a contact terminal 93, while the other free end thereof is adapted to engage with and be disengaged from a contact 95. The thermal timer 89 includes also a heating coil 97 operatively associated with the bimetal bar 91. One terminal of coil 97 is connected to conductor 71, and through this conductor to the second supply circuit conductor 55. Contact terminal 95 of thermal timer 89 is connected by a conductor 99 to the other terminal of cell 51 and of coil 69. Contact 93 is connected by a conductor 101 with the other terminal of coil 83 of the second electromagnetic switch 73. One terminal of heater 21 is connected to contact terminal 31 of the lower heater control switch 25, while the other terminal of heater 21 is connected by a conductor 103 with fixed contact 75 of the second electromagnetic switch 73. Contact terminal 31 of switch 25 is connected by a conductor 105 with one terminal of heating coil 49 of the thermal retarder 33, the other terminal of heating coil 49 being connected by a conductor 107 with contact 43 of the thermal retarder 33, which contact is

connected by a conductor 109 with contact terminal 61 of the first electromagnetic heater control switch 59. The second contact terminal 45 of switch 33 is connected by a conductor 111 with conductor 103. Fixed contact 71 is connected by a conductor 113 to the first supply circuit conductor 53. Fixed contact 63 is connected to supply circuit conductor 53.

Let it be assumed, for purpose of illustrating the operation of the control system embodying my invention, that heater 21 was energized during night hours, so that at the time when the light sensitive cell 51 became subject to daylight, all of the water in the tank had been heated to a predetermined high temperature, which, as hereinbefore stated, is on the order of 150° F. When all, or substantially all, of the water in the tank had been heated to this high temperature, the bimetal bar 27 moved out of engagement with fixed contact member 31, with the result that the heater control system was deenergized with attendant deenergization of heater 21. If this occurred during night hours, contact bridging member 65 would still have been in engagement with fixed contacts 61 and 63 and switch arm 41 would have been in engagement with contact terminals 41 and 43 of the thermal retarder switch 33.

However, when the light sensitive cell 51 became subject to daylight, it would conduct current therethrough, which would result in an energizing current flowing through coil 69 through the following circuit: from supply circuit conductor 53, through conductor 57, cell 51, coil 69, conductor 71, and to the second supply circuit conductor 55. This would energize core 67 and cause lifting of the contact bridging member 65 out of engagement with contacts 61 and 63; whereby, as will be evident from inspection of the connections shown in Fig. 2, the circuit comprising heater 21 would be opened.

Let it now be assumed that hot water is used in the early daylight hours, with the result that the lower thermal switch 25 is subject to cold water, with the result that bimetal bar 27 would move into engagement with contact 31. This, however, would not have any other effect because of the disengagement of contact bridging member 65 with contacts 61 and 63. However, an energizing circuit will be closed through heating coil 97 of the thermal timer 89, which energizing circuit may be traced as follows: from the first supply circuit conductor 53, through conductor 57, light sensitive cell 51, conductor 99, coil 97, and from and through conductor 71 to the second supply circuit conductor 55. It may be here noted that the wattage of heating coil 97 is relatively small so that it will require from say five to six hours before the bimetal bar 91 will have been heated sufficiently to cause it to move into engagement with fixed contact member 95. Thus, if hot water was withdrawn from the tank at say 7 a. m., the quantity withdrawn being sufficient to cause the entry of enough cold water into the bottom end of the tank to subject switch 25 thereto, bimetal bar 91 would be moved into engagement with contact 95 at a time on the order of 12 noon or 1 p. m. This would cause a current to flow through coil 83 of the second electromagnetic switch 73, this circuit being traceable as follows: from supply circuit conductor 53, through conductor 57, cell 51, conductor 99, contact 95, bar 91, contact 93, conductor 101, coil 83, and conductors 85 and 87, to the second supply circuit conductor 55. This

current will cause a raising of the core 81, with the attendant result that contact bridging member 79 will be moved into engagement with contacts 75 and 77 so that an energizing circuit through heater 21 is closed, which circuit may be traced as follows: from supply circuit conductor 55, through conductor 81, through the closed lower switch 25, heater 21, conductor 103, contacts 75 and 77, and contact bridging member 79, and through conductor 113 to the other supply circuit conductor 53.

It is evident that energization of heater 21 of the hot water tank 11 will be delayed for a length of time, during daylight hours, that will cause its energization to take place during the off-peak daylight period, which generally speaking, is usually to be found to occur at, or shortly after, 12 noon. The length of time during which energization of the heater 21 will continue, depends, of course, upon the amount of cold water which entered the tank to replace the hot water used from the tank; but when substantially all of the water in the tank is hot, bimetal bar 27 of the thermal switch 25 will interrupt the circuit.

Let it now be assumed that a relatively small quantity of hot water is drawn from tank 11 during the early night hours, during which time contact bridging member 65 will be in engagement with contacts 61 and 63. If only the lower thermal switch 25 is subject to cold water, an energizing circuit through heating coil 49 will be effected, which circuit may be traced as follows: from supply circuit conductor 53, through the engaged contact bridging member 65 and contacts 61 and 63, through conductors 109 and 107, coil 49, through conductor 105, through the lower thermal heater control switch 25, and from and through conductor 87 to the second supply circuit conductor 55. As has been hereinbefore set forth, the length of time required to cause temperature rise of the low expansion rod 39 to a temperature on the order of 300° F. is five to six hours, so that in case say bimetal bar 27 was moved into engagement with contact 31 at 7 p. m., with attendant energization of coil 49 at that time, it would be 12 midnight or 1 a. m. before switch arm 41 would again be moved into engagement with contacts 43 and 45. Energization of heater 21 will then be effected and will continue until substantially all of the water in the tank is hot, when movement of bimetal bar 27 into open position will take place, with attendant deenergization of heater 21.

Let it now be assumed that a relatively large amount of hot water was withdrawn from the tank during the early evening or night hours, so that the thermal retarder switch 33 will also be subject to cold water. This will result in contraction of the high expansion rod 35, with attendant movement of switch arm 41 into closed position, that is into engagement with contact terminals 43 and 45. This will close energizing circuit through heater 21, which circuit may be traced as follows: from supply circuit conductor 55, through conductor 87, through the lower switch 25, heater 21, conductors 103 and 111, through the closed thermal retarder switch comprising contact terminals 45 and 43 and switch arm 41, through conductor 109, to the engaged contacts 61 and 63 and contact bridging member 65, and to the other supply circuit conductor 53.

In other words, if a relatively large quantity of hot water has been withdrawn from the tank during the early evening or night hours, energization of the heater 21 will occur simulta-

neously with the subjection of the thermal retarder heater control switch 33 to cold water, and such energization will continue until the thermal retarder switch is again subject to hot water, when the switch arm 41 will be moved out of engagement with contact terminals 43 and 45, provided that the heating coil 49 has not been energized long enough to cause temperature rise of the second low expansion rod 39 to a length sufficient to maintain switch arm 41 in engagement with contacts 43 and 45; but when coil 49 has been energized for a length of time on the order of five to six hours, the second expansion rod 39 will have been raised to a temperature sufficient to cause its length to again be substantially the same as that of the first expansion rod 35, with attendant closure of the switch controlled by the two thermally-expansible rods. Closure of the thermal retarder switch will again cause energization of heater 21 through the circuit hereinbefore described, which energization will continue until substantially all of the water in the tank is hot, when the lower thermally-actuable switch 25 will cause deenergization of heater 21 in the manner hereinbefore described.

Various modifications may be made in the system embodying my invention without departing from the spirit and scope thereof, and all such modifications coming clearly within the scope of the appended claims shall be considered as covered thereby.

I claim as my invention:

1. A control system for an electric heater for a hot water tank, comprising a main thermally-actuable heater control switch subject to tank water temperature at the lower end portion of the tank and adapted to be in closed position when subject to cold water, a second heater control switch means controlled by a light-sensitive cell to be in open position during daylight hours and in closed position during night hours, a third heater control switch electrically connected in shunt circuit relation to said second switch and adapted to be normally in open position and a thermal timer means effective to cause movement of said third switch into closed position to effect energization of said heater with a predetermined time period of delay after daybreak in case said main switch is subject to cold water at daybreak.

2. A control system for an electric heater for a hot water tank, comprising a main thermally-actuable heater control switch subject to tank water temperature at the lower end portion of the tank and adapted to be in closed position when subject to cold water, a second heater control switch means controlled by a light-sensitive cell to be in open position during daylight hours and in closed position during night hours, a third heater control switch electrically connected in shunt circuit relation to said second switch and adapted to be normally in open position and a thermal timer means effective to cause movement of said third switch into closed position to effect energization of said heater with a predetermined time period of delay after said main switch becomes subject to cold water during daylight hours.

3. A control system for an electric heater for a hot water tank, comprising a main thermally-actuable heater control switch subject to tank water temperature at the lower end portion of the tank and adapted to be in closed position when subject to cold water, a second heater control switch controlled by a light sensitive cell

to be in open position during daylight hours, a thermal retarder heater control switch subject to tank water temperature intermediate the ends of the tank connected in series circuit with said main and said second switch, said thermal retarder switch being selectively effective during night hours to cause energization of said heater with a time period of delay and immediately in accordance with the amount of cold water in the tank, an electromagnetic switch connected in shunt circuit relative to said second and said thermal retarder switch and a thermal timer means controlled by said light sensitive cell to cause closing of said electromagnetic switch and energization of said electric heater with a predetermined time period of delay after said main switch becomes subject to cold water during the daylight hours.

4. A control system for an electric heater of a hot water tank, comprising a first thermally-actuable heater control switch subject to tank water temperature at the lower end portion of the tank and adapted to be in closed position when subject to cold water, a second heater con-

trol switch subject to tank water temperature intermediate the ends of the tank adapted to be in closed position when subject to cold water in the tank and adapted to be moved into closed position with a predetermined time period of delay when subject to hot water in the tank, a third heater control switch connected in series circuit with said first and said second switch and said heater, a light sensitive cell for controlling said third switch to be open during daylight hours and closed during night hours, a fourth heater control switch connected in shunt circuit to said second and third switches and a thermal timer means controlled by said light sensitive cell to cause closure of said fourth switch and attendant energization of said heater with a predetermined time period of delay during daylight hours in case said first switch is subject to cold water during daylight hours.

5. A control system as set forth in claim 4, in which said first switch is effective to deenergize the heater when substantially all of the water in the tank is hot.

CLARK M. OSTERHELD.
